FURFURAL RECOVERY

Charles Keith Buell and Charles F. Weintraub,
Borger, Tex., assignors to Phillips Petroleum
Company, a corporation of Delaware

Application February 8, 1945, Serial No. 576,856

2 Claims. (Cl. 260—347)

1

The invention relates to the recovery of furfural from admixture with hydrocarbon contaminants. For example, furfural used as an extractive distillation solvent in hydrocarbon recovery processes may accumulate contaminants which may result in reducing the effectiveness of the furfural as a solvent for the desired hydrocarbon through foaming in the extractive distillation and stripping steps.

For example, in butadiene manufacturing processes wherein furfural is used as the selective solvent to separate certain of the C₄ hydrocarbons, especially butylenes and/or butadiene, from others, small quantities of hydrocarbon impurities, having a lower volatility than C₄'s, which have not been completely eliminated in preparing the C₄ concentrate, enter the furfural system, or low volatility hydrocarbons may be generated in the furfural extraction system by polymerization or other reaction mechanisms, or such relatively non-volatile hydrocarbons may gain entrance into the furfural system through valve, compressor, pump, etc., lubricating devices. These contaminants will hereinafter be referred to as "oils."

Generally, if these oils are kept at a concentration below about one weight per cent the foaming of the furfural in the extractive distillation and stripping steps will not be excessive. The present invention provides a method for maintaining the concentration of such oils at a low level. These oils generally are not readily removed from furfural by ordinary means, such as fractional or steam distillation, because they either form azeotropes with the furfural or boil close to the furfural so that separation by ordinary fractional distillation to obtain a pure furfural or pure oil concentrate is impractical if not impossible.

We have found that water extraction can be used effectively for separation of furfural from contaminating oils. Our invention provides a satisfactory and commercially feasible method of water extraction of the furfural-oil mixture to resolve same into separate fractions of substantially oil-free furfural and substantially furfural-free oil.

The present invention has for its principal object the provision of an improved method of recovering furfural from hydrocarbons such as oils of the type described above. Another object is to provide a suitable method of accomplishing this by means of water extraction. Another object is to accomplish this result with a minimum of equipment investment and in a simple and

2

easily controlled manner. Another object is to provide such a method which is applicable to the oil-furfural mixture obtained by the extraction of oil-contaminated furfural with a light hydrocarbon solvent and evaporation or distillation of the solvent from the extract phase, as disclosed in U. S. Patent 2,414,402, to Thodos et al., which issued January 14, 1947. Numerous other objects of the present invention will more fully herein-after appear.

In the accompanying drawings:

Fig. 1 portrays diagrammatically one arrangement of equipment used in a two-step water extraction process in accordance with the present invention. Fig. 2 shows an arrangement in which the water extraction is conducted countercurrently in an extraction column. Fig. 3 shows a modified arrangement in which provision is made for preliminary concentration of the furfural-hydrocarbon mixture.

It is disclosed in the copending application of Thodos and Weintraub, above-identified, that foaming oils may be removed from furfural contaminated therewith by liquid-liquid extraction with a hydrocarbon solvent immiscible with furfural whereby the foaming oils dissolve in the hydrocarbon, and separation of the hydrocarbon phase from the resulting furfural phase. The furfural phase (raffinate) may be fractionally distilled to recover dissolved hydrocarbon solvent. The hydrocarbon phase (extract) may likewise be distilled to recover the hydrocarbon solvent which may be recycled to the extraction, leaving a residual mixture of the foaming oils and furfural. The process of the present invention may be applied to such a residual oil-furfural mixture to enable the recovery of the valuable furfural content thereof in uncontaminated form.

In accordance with our invention the furfural-oil mixture is first extracted with water in amount sufficient to dissolve most or substantially all of the furfural. The amount of water required will depend upon the concentration of furfural in the mixture being extracted, the concentration of furfural in the raffinate, upon the temperature of extraction and upon other factors. In general, the amount of water employed should be sufficient so that nearly all of the furfural can go into solution in the water under the conditions of temperature and pressure prevailing in the extraction zone. It will be understood, of course, that an equilibrium is involved between the furfural in the aqueous phase and that in the hydrocarbon phase so that in practice a small amount of furfural appears in the raffinate. Usually the

amount of water extractant used is such that the resulting aqueous phase is considerably less than saturated (say not over 50% down to 25% saturated) with furfural under the extraction conditions. Often the concentration of furfural in the aqueous phase is less than 10 or even 5 weight per cent. The amount of water employed greatly exceeds the proportion of water in the azeotrope of furfural and water so that a high temperature is not required in order to keep the aqueous phase as a single phase and so that in the subsequent fractional distillation of the aqueous phase the azeotrope will go overhead leaving water as a bottom product. It will be understood that by using such an amount of water that the resulting extract phase is far from saturated with respect to furfural under the extraction conditions a better recovery of furfural is attained since the equilibrium ratio of furfural dissolved in the water to furfural dissolved in the oil is greater with greater ratio of water to oil. In general, it is preferred that the aqueous phase of furfural and water resulting from the extraction be not over 50% ranging downwardly to about 25% of saturation. The solubility of furfural in water depends upon the temperature. Mains (Chem. Met. Eng. 26, 779 (1922)) gives the following data:

<i>t</i> , ° C.	gms. furfural per 100 gms. H ₂ O
10	7.9
20	8.3
30	8.8
40	9.5
50	10.4
60	11.7
70	13.2
80	14.8
90	16.6

Usually sufficient water is employed that the resulting aqueous phase contains not more than 5% and frequently not more than 3% by weight of dissolved furfural. Use of an excessive amount of water in the extraction step is often undesirable because the heat consumption in the subsequent azeotropic distillation step applied to the extract phase is excessive.

The temperature at which the water extraction of the present invention is conducted may vary within wide limits, for example, from about 50 to about 300 degrees F. Temperatures ranging from about 90 to about 150 degrees F. are preferred, however. While it is possible to carry out the extraction at temperatures equal to or above the critical solution temperature for proportions of furfural and water which would not normally be completely miscible, it is preferred to use such a proportion of water that all of the furfural can dissolve therein at moderate temperatures of not over 150 degrees F., since as is explained above much better recovery of furfural from oil is thereby obtained, the loss of furfural in solution in the oil phase being at a minimum. Another advantage of the use of a large amount of water, so that a dilute aqueous phase with respect to furfural results, is that the solubility of oil in such a dilute aqueous phase is very low whereas as the aqueous phase becomes saturated with furfural the solubility of oil therein increases. Another advantage of the use of moderate temperatures, i. e., not over 150 degrees F., is that the amount of oil dissolved in the aqueous phase is minimized since the solubility of oil in aqueous furfural rises with increasing temperature.

The pressure at which the extraction is conducted may depend somewhat on the tempera-

ture, usually ranging from atmospheric to moderately superatmospheric. The extraction is generally conducted in closed pressure-resisting equipment in order to minimize losses by volatilization.

The water extraction may be carried out in any suitable way, for example, by intimately mixing the water and furfural-oil mixture in a mixing pump or other adequate mixing means and then allowing the mixture to separate into two phases or layers in a settling zone or chamber or by continuously countercurrently contacting the water extractant and the furfural-oil mixture in a column equipped with contacting means such as bubble caps, packing, etc. The operation may be either single stage or multi-stage and may be carried out either batchwise or continuously. The two phases, namely, extract and raffinate, are separately withdrawn in the usual manner. The oil phase (raffinate) is generally discarded.

Preferably conditions of extraction are so adjusted in accordance with the principles herein disclosed that the raffinate does not contain more than 3 weight per cent of furfural and so that the extract phase contains considerably less than 0.1 weight per cent of oil. The former limitation insures against excessive loss of furfural and the latter specification insures that the purified furfural product contain not over 0.1 weight per cent of hydrocarbon.

The water-furfural phase is then subjected to fractional distillation to separate the azeotrope of furfural and water overhead from a bottoms product composed essentially of the remainder of the water which is recycled to the water extraction unit in order to save water and the small amount of furfural which may be left therein. The overhead vapors are cooled and totally condensed and the condensate caused to form two separate liquid layers. The upper aqueous layer is totally refluxed to the azeotrope column while the lower layer constitutes the oil-free furfural product of the invention.

If desired, a small continuous stream of the lean furfural from an extractive distillation-stripping zone may be treated in accordance with the present invention, being water-extracted and the purified furfural being recovered from the resultant furfural-water mixture and continuously returned to the furfural extractive distillation zone. However, it is generally desirable to first concentrate the oils since they represent only a small percentage of the furfural in a furfural extraction zone. Without first concentrating these oils an excessively large volume of water would be required to extract the furfural and excessively large amounts of heat would be required in concentrating the furfural in the resultant furfural-water mixture. Concentration of these oils can be accomplished by fractionation. Apparently, the previously suggested azeotropes of furfural and oils, if actually formed, are of the minimum boiling type. This, coupled with the fact that these oils boil close to furfural, but usually at a

slightly lower temperature, makes it possible to prepare a concentrate of these oils but impossible to effect complete separation between the furfural and oils by fractionation. In other words, the oils plus some furfural can be removed by fractionation as an overhead product leaving a relatively oil-free furfural bottom product. This can be used as a method for removing oils from furfural but is not satisfactory because it necessarily results in high furfural losses. By using the water extraction method of my invention in conjunc-

tion with an oil concentration step of this type, substantially complete removal of oil contaminants from furfural can be effected without the furfural loss which would be involved in an attempt to use fractional distillation only.

By water extracting the oil concentrate prepared as just described the furfural can be removed from the oil. Two liquid phases result from such treatment, a water-furfural rich phase and a hydrocarbon-oil rich phase. These phases can be collected separately, thereby effectively removing the oils from the furfural. The water-furfural rich phase is then fractionally distilled to recover the furfural-water azeotrope as the overhead product and water as the bottom product. By condensing and cooling the overhead product, two liquid phases are obtained, a furfural-rich phase with only a small percentage of water and a water-rich phase with a small percentage of furfural. The two phases are separated from each other. The water-rich phase is totally refluxed to the fractionation column. The furfural-rich phase constitutes the purified furfural product which may be returned to the furfural extractive distillation and stripping zone of the hydrocarbon recovery process for which the furfural is being used or further processed, stored, etc. This furfural product contains a small percentage of water. However, this is usually advantageous since a small percentage of water is generally maintained in furfural used in the extractive distillation of light hydrocarbons in order to lower the boiling point of the furfural and thereby decrease the tendency for furfural polymer formation in the extractive distillation and stripping steps. A further advantage is that the selectivity of the furfural for extractive distillation purposes is increased by the presence of small amounts of water. The use of furfural containing dissolved water in the extractive distillation of C₄ hydrocarbons (butene and/or butadiene) is described in the U. S. Patent 2,434,796, issued to Hachmuth on January 20, 1948.

The bottom product of the fractionator in which the water-furfural phase is distilled consists primarily of water and may be recycled to the water extraction zone.

If the contaminating hydrocarbons have reached a high concentration, the hydrocarbon-furfural mixture is often first subjected to fractional distillation to remove without furfural loss as much as possible of any hydrocarbons boiling below furfural but above the hydrocarbons for which the furfural was used as a solvent extraction agent. This concentrates the furfural but does not remove the hydrocarbons having boiling points close to that of furfural. By mixing this furfural concentrate with a sufficient amount of water to dissolve the furfural, as before, and allowing to settle, two liquid phases result. By reason of the greater solubility of the furfural in water than the hydrocarbons the lower layer is a water-furfural rich phase and the upper layer is a hydrocarbon-rich phase containing essentially all of the oils which contaminated the furfural. The furfural-rich phase is then fractionated to recover the furfural-water azeotrope as the overhead product and water as the bottom product. The furfural-water azeotrope is condensed and cooled as before giving two liquid phases, the lower phase being furfural saturated with water and the upper layer being water saturated with furfural at the existing temperature conditions in the overhead product accumulator. The water-rich phase is used to reflux the col-

umn. The furfural-rich phase is withdrawn from the accumulator. This product constitutes the purified furfural and is returned to the solvent extraction process or to solvent storage.

6. Normally furfural recovered by this method will contain about 6 weight per cent water. If dry furfural is desired further processing will be necessary. However, for butadiene or butylene recovery it has been found advantageous to use furfural containing about 4 to 8 weight per cent of dissolved water.

The bottom product from the furfural-water fractionator, consisting of water, may be used in the step wherein the contaminated furfural is dissolved in water.

The hydrocarbon product from the settling zone used in the water extraction of the furfural, the upper phase, may be discarded or further processed. However, it will usually still contain appreciable amounts of furfural. Consequently, it will usually be desirable to subject this product to a second water extraction step, in which case the water from the bottom of the furfural-water fractionator may be used as the extraction agent.

20. The hydrocarbon-water-furfural mixture from this second extraction step is allowed to settle. Two liquid phases separate, one consisting primarily of hydrocarbon with only small amounts of dissolved furfural and the other consisting of

25. water with the furfural recovered from the hydrocarbon. The hydrocarbon phase is removed from the system for disposal, storage, or further processing, etc. The water phase containing the small amounts of furfural recovered from the hydrocarbon may be used as the water extraction agent in the first extraction zone.

The mixture of furfural and hydrocarbon treated in accordance with the present invention preferably contains about 20 weight per cent of hydrocarbon, the balance being furfural. If the mixture contains less hydrocarbon than this it is preferably first distilled fractionally to concentrate the hydrocarbon.

45. Referring now to the drawings:

Fig. 1 shows a simplified flow diagram of one modification of the invention applicable to any concentration of furfural and contaminating oils. In the drawing furfural contaminated with oils is introduced by means of line 1 into line 3 and finally into pump 4. A water-rich stream is also introduced into mixer or centrifugal pump 4 by means of lines 2 and 3. In pump 4 the water and furfural are intimately mixed and discharged into settler 6 by means of line 5. In settler 6 two liquid phases separate, the upper phase rich in hydrocarbon and the lower phase rich in water and furfural. The lighter oil rich phase flows over vertical baffle 6A in settler 6 thereby separating the heavier water-furfural mixture from the lighter oil contaminant mixture. The oil contaminant is removed from settler 6 through line 7. The water-furfural mixture is removed from settler 6 and introduced into fractionator 9 through line 8. In fractionator 9 the water-furfural mixture is fractionated to obtain the water-furfural azeotrope as the overhead product and substantially all water as the bottom product. The overhead product is removed from column 9 by means of line 10 and introduced into cooler 11 where the product is totally condensed and cooled. From cooler 11 the liquefied and cooled product is introduced into overhead product accumulator 13 by means of line 12. Two liquid phase separation occurs in accumulator 13, the upper phase being a

water-rich phase containing a small percentage of furfural and the lower phase being a furfural-rich phase containing a small percentage of water. The water-rich phase is totally returned to column 9 as reflux by means of line 15. The furfural-rich phase is withdrawn from accumulator 13 by means of line 14. This constitutes the purified furfural product and it may be sent to storage, further processing, or returned to the extractive distillation and stripping zones of a hydrocarbon recovery process.

The oil-rich phase from settler 6 is introduced by means of line 7 into line 21 and mixer or centrifugal pump 22. The bottom product, consisting mostly of water, from fractionator 9 is also introduced into line 21 and pump 22 by means of lines 16, 18 and 20. In pump 22 the oil contaminant and water are intimately mixed. The mixture is discharged from pump 22 through line 23 into settler 24 where two liquid phase separation occurs, the upper phase being oil rich and the lower phase being water-furfural rich. The upper phase, oil rich, flows over baffle 24A and is discharged from the system through line 25. The water-furfural rich phase is conducted by means of line 2 into line 3 and pump 4 as previously described.

Line 17 connecting to line 18 at the bottom of column 9 is provided for removal or drainage of water from the system if desired. Line 19 connecting with line 20 is provided for adding water as needed to replace any lost from the system through leaks, or carried out of the system by solution or entrainment in the oil and furfural products, etc.

By proper location of the effluent lines from settlers 6 and 24 and regulating the rate of withdrawal of products so that these vessels run liquid full, it should be noted that baffles 6A and 24A can be eliminated. Thus lines 7 and 25 can be located to withdraw from the tops of vessels 6 and 24, respectively, for this purpose. Usually baffles are desirable; however, if desired, baffles may be used in some settlers in a multiple stage extraction process and not in others depending on the purpose to be achieved.

Two stages of extraction are shown in Figure 1, however, it is to be understood that any number of stages of extraction from one to any greater number as desired or necessary for effecting the recovery of the furfural from the oil contaminant may be employed.

As previously mentioned, the above described process for removing oil contaminants from furfural is applicable to any concentration of furfural and contaminant. In the preparation of a contaminant concentrate, also previously described, a mixture of oil contaminant and furfural is sometimes obtained which is less dense than water. With a mixture of this type it is frequently more desirable to use countercurrent contacting in a packed tower wherein water is introduced at or near the top and the oil contaminant-furfural mixture near the middle or bottom. A modification of this type is depicted by Figure 2. In Figure 2, furfural contaminated with oils is introduced into packed tower 26 through line 1 near the bottom of the tower. In tower 26 the contaminated furfural is countercurrently contacted with water introduced near the top of the tower through line 27. Water-furfural solution is withdrawn from the bottom through line 28. Hydrocarbon contaminant or oil is withdrawn from the top through line 25. This latter stream may be discarded, stored, fur-

ther processed, etc. Frequently it will be desirable to subject it to another or more stages of extraction with water to remove the final traces of furfural.

The water-furfural extract from the bottom of tower 2 is fed by means of line 28 to fractionator 9. In fractionator 9 the furfural-water azeotrope is obtained as the overhead product which is conducted by means of line 10 to condenser and cooler 11 to totally condense the overhead product. The cooled condensate from 11 is introduced by means of line 12 into accumulator 13 and allowed to settle. Two liquid phases separate in 13, a furfural-rich and a water-rich phase. The total water-rich phase is supplied to fractionator 9 as reflux by means of line 15. The furfural-rich phase is removed from accumulator 13 through line 14 as the purified furfural product which may be sent to storage, further processing, or returned to the extractive distillation and stripping zones of a hydrocarbon recovery process.

The bottom product from fractionator 9 consists primarily of water and is removed through line 16. This water may be discarded from the system through drain line 17 or recycled to the extraction zone 26 by means of lines 18 and 21. Usually it will be desirable to recycle the water from fractionator 9 to the water extraction zone 26.

Line 19 connecting with 18 is provided, as in Fig. 1, for adding water to the system. Generally, a small amount of water will have to be continuously added to the system to make up for the small amounts carried out in solution or entrainment with the hydrocarbon and furfural products.

The modification of Fig. 2 is not applicable to oil-furfural mixtures more dense than water, even though the water be introduced at the bottom of tower 2 and the oil-furfural mixture at the top. In this arrangement, at some point in the process of extraction, the density of the incompletely extracted oil-furfural mixture and the resultant water-furfural mixture will become equal and no further contacting will occur.

In Fig. 3, furfural containing hydrocarbon contaminant is fed to fractionator 31 to concentrate the furfural by removing hydrocarbons boiling at a lower temperature than furfural, but at a higher temperature than the hydrocarbons for which the furfural was used as a selective solvent. The fractionator is usually preferably operated such that substantially all of the furfural is retained in the kettle product. The hydrocarbon overhead product is condensed and collected in accumulator 32. A portion of the hydrocarbon is used as reflux to the column and the remaining portion is removed from the system for storage, disposal, or further processing, etc. If there is water present in the furfural feed to the column at least a portion of it will constitute a part of the overhead product, in which case two liquid phases will separate in accumulator 32. The water phase may be discarded or returned to the system in the extraction zone to recover any furfural that might be retained therein. The bottom product from tower 31 passes via line 33 through cooler 34 and is intimately mixed with water from line 35 in sufficient quantity to dissolve the furfural. The water-furfural-hydrocarbon mixture is introduced into extraction settler 36 and allowed to separate into two liquid phases, the upper phase being rich in hydrocarbon and the lower phase rich in furfural.

and water. The water-furfural phase is fed via line 37 to fractionator 38. In fractionator 38 furfural-water azeotrope constitutes the overhead product. The overhead product is totally condensed and collected in accumulator 39. Two liquid phases separate, the lower phase being furfural saturated with water at the temperature of the accumulator and the upper phase being water saturated with furfural at the accumulator temperature. The water-rich phase is totally refluxed to column 38. The furfural-rich phase is the purified furfural product which is withdrawn from the system and sent to storage, or returned to the butadiene recovery step, or further processed for water removal, etc.

The bottom product of fractionator 38 consists of water primarily. This water is recycled via line 40 and cooler 40A to extraction settler 41. The function of extraction settler 41 is described hereafter.

The hydrocarbon phase from extraction settler 36 usually will still contain appreciable amounts of furfural. Consequently, it is desirable that this product be subjected to a second water wash to recover the last traces of furfural. Hydrocarbon product from 36 is thoroughly mixed with water, the bottom product from fractionator 38, and introduced into extraction settler 41. Two liquid phases separate in 41; a water-rich phase with a small amount of furfural constitutes the bottom layer and hydrocarbon with a relatively low furfural content constitutes the upper layer. The lower layer from extraction settler 41 is recycled as the water extraction agent via line 35 to extraction-settler 36. The hydrocarbon upper layer was withdrawn via line 42.

Example

Using the equipment of Fig. 3, furfural containing 81.5 weight per cent hydrocarbon was fed to fractionator 31. A temperature of 310 F. was maintained at the bottom of the fractionator and 188 F. at the top. The overhead product accumulator 32 was maintained at 100 F. The overhead product had the following composition: 40 99.0 weight per cent hydrocarbon and 1.0 weight per cent furfural. A portion of the overhead product from fractionator 2 was returned as reflux. A reflux ratio of about 1.8 to 1, based on the overhead product, was maintained. The overhead make was removed from the system. The bottom product consisted of 70.0 weight per cent hydrocarbon and 30.0 weight per cent furfural. This product was cooled to about 100 F. and mixed with sufficient water to dissolve most of the furfural and introduced into extraction settler 36. Two liquid phases separated, the upper layer rich in hydrocarbon and the lower layer rich in water and furfural. The upper layer had the following composition: 45 88.9 weight per cent hydrocarbon and 11.1 weight per cent furfural. The lower layer consisted of 2.5 weight per cent furfural and 97.5 weight per cent water. The water-furfural layer was fed to fractionator 38 where the furfural-water azeotrope was taken overhead and water out the bottom. A bottom temperature of 212 F. and a top temperature of 208 F. was maintained in fractionator 38. Fractionator 38 and its overhead product accumulator 39 were maintained at substantially atmospheric pressure. The overhead product was 50 condensed and cooled to 100 F. In accumulator 39 two liquid phases separated; the lower phase consisted of 93.2 weight per cent furfural and 6.8 weight per cent water and the upper phase consisted of 8.0 weight per cent furfural and 92.0 weight per cent water. The upper phase was totally refluxed to column 38. The lower phase constituted the purified furfural product which was removed from the system.

5 The bottom product from fractionator 38, consisting of 0.025 weight per cent furfural and 99.975 weight per cent water, was cooled and mixed with the hydrocarbon product from extraction-settler 36 to remove most of the furfural remaining in the hydrocarbon product. This mixture was then introduced into extraction-settler 41. Two liquid phases separated in extraction-settler 41, an upper phase rich in hydrocarbon and a lower phase rich in water and furfural. The upper phase, consisting of 97.9 weight per cent hydrocarbon and 2.1 weight per cent furfural, was removed from the system. The lower phase, consisting of 0.7 weight per cent furfural and 99.3 weight per cent water, was recycled to be mixed with the bottom product from fractionator 31 as the water extraction agent and subsequently introduced into extraction settler 36.

Generally, it will be desirable to maintain a slight positive pressure throughout the system to prevent the possibility of air leaking in and promoting furfural polymerization. High pressures are undesirable because of the high temperatures that would be required in the fractionation system thereby promoting furfural polymerization. Where the desired pressures cannot be attained at the operating temperatures such as in the overhead product accumulators on the fractionators, the extraction-settlers, etc., residue gas may be used for pressuring and maintaining pressure on these vessels.

For example, in operating according to the above described procedure, the pressure in accumulator 32, when totally condensing the overhead product from fractionator 31 and cooling to 100 F., may actually be below atmospheric. Consequently, in order to prevent the possibility of drawing air into the accumulator a pressure of about 10 pounds gage was maintained by introducing residue gas into the accumulator. Pressure was maintained on the extraction-settler 36 by the same means. Extraction settler 41 was operated liquid full. Column 38 and accumulator 39 were operated at substantially atmospheric pressure. However, to insure against air leaking into the system a blanket of residue gas at a very slight positive pressure was maintained in accumulator 39.

It is to be understood that there are several possible modifications of this invention, among which 55 are use of a larger number of steps of water extraction than described. In some instances it may not be necessary or desirable to employ the fractionation step performed by fractionator 31 of Fig. 3, especially in cases where the furfural concentration of the product to be purified is high or the concentration of the relatively lighter hydrocarbons is low.

From the foregoing many advantages of the process of the present invention will be apparent to those skilled in the art. Principal among these 60 advantages is the excellent recovery of furfural made possible by the present process. Other advantages are the simplicity, ease of control and economy of the process and the small amount of relatively simple and not unduly expensive equipment required. Another advantage is that the conditions in the several steps of the recovery process are readily adjusted by the operators so as to minimize loss of furfural in the oil fraction and by polymerization. Another advantage is

that no, or practically no, furfural is lost by polymerization since the furfural is not subjected to high temperature. Another advantage is that loss of furfural in solution in the oil or raffinate is very low by reason of the conditions of the water extraction, namely, the large ratio of water to furfural and the moderate temperatures employed. While there is employed an excess of water over that required to dissolve all of the furfural from the furfural-oil mixture in the extraction step, this excess is not sufficiently great as to require an excessive expenditure of heat in the subsequent fractional distillation step applied to the water extract. In this way we obtain the advantages of an excess of water over that required to give a saturated solution of furfural without the disadvantage of an excessively large amount of water. Numerous other advantages of the present invention will be apparent.

We claim:

1. The process of recovering furfural from admixture with foam producing oils which are not readily removed from furfural by distillation which comprises extracting such furfural-oil mixture with water at a temperature in the range from 90° to 150° F., controlling the quantity of water used in the extraction so that the resulting aqueous phase is from 50 to 25 per cent saturated with furfural, separately withdrawing said aqueous phase and a resulting oil phase, subjecting said aqueous phase to fractional distillation in a fractionation column and thereby separating it into an overhead fraction of furfural and water in azeotropic proportions and a bottoms fraction of water, condensing said overhead and causing the liquid condensate to separate into a water phase and a furfural phase

essentially free of oils, withdrawing said water phase and refluxing said column therewith, and separately withdrawing said furfural phase as the product of the process.

5. The process of recovering furfural from admixture with foam producing oils which are not readily removed from furfural by distillation which comprises extracting such furfural-oil mixture with water at a temperature in the 10 range from 90° to 150° F., controlling the temperature and quantity of water in the extraction so that the resulting aqueous phase does not contain more than 0.1 weight per cent of oils and the resulting oil phase does not contain more than 3 weight per cent of furfural, separately withdrawing said aqueous phase and oil phase, subjecting said aqueous phase to fractional distillation in a fractionation column and thereby separating it into an overhead fraction of furfural and water in azeotropic proportions and a bottoms fraction of water, condensing said overhead and causing the liquid condensate to separate into a water phase and a furfural phase
- 15 essentially free of oils, withdrawing said water phase and refluxing said column therewith, and separately withdrawing said furfural phase as the product of the process.
